UNITED STATES PATENT OFFICE.

JAMES W. KEENAN, OF FARMINGTON, MICHIGAN.

COMBINED MUFFLER AND HEATER.

Application filed August 12, 1926. Serial No. 128,774.

This invention relates to new and useful improvements in combination mufflers and heaters for automobile vehicles, and has for its object the provision of a muffler which gives maximum heating surface area for the heater associated therewith, and which includes means to provide for the shrinkage in volume of the gases caused by the drop of temperature of the gases, whereby the efficiency of the muffler is increased.

Another object of the invention is to provide a muffler having minimum back pressure.

Other objects of the invention will appear hereinafter.

In the drawing:

Figure 1 is a plan view of a device illustrative of the invention and having the casing thereof in section;

Figure 2 is a longitudinal vertical section of the same; and

Figure 3 is a cross sectional view taken on the line III—III of Figure 2.

Similar characters of reference indicate corresponding parts.

Referring to the drawing:

The heating and muffling element, according to the present invention as shown, comprises a cast inlet header 10, a cast outlet header 11 of smaller dimension than the inlet header, and a sheet metal conduit 12 connected into the said headers at its ends as indicated at 13 (Figure 2).

The inlet header 10 is hollow and formed preferably of cast iron, and has a depending transverse internal dividing wall 14, and an outer laterally extending supporting flange 15 formed with a central aperture in which is inserted an end of the exhaust pipe 16. Said supporting flange 15 also serves as a supporting end wall for the casing hereinafter described, and has an opening 17 to permit air to enter said casing. The inlet header 10 also has formed integral therewith or otherwise carried thereon, a series of radiating fins 18, which may be positioned on the upper side thereof as shown, or upon both sides. The outlet header 11 is also hollow and formed preferably of cast iron, and has an opening 19 within which the end of an exhaust pipe 20 is inserted, said pipe extending loosely through the central aperture 21 formed in the plate 22 forming the other end wall of the heater casing, said plate serving as a support for the outlet header 11, the connec-

tion being such as to permit the expansion of the manifold conduit 12 without damaging the heater casing.

The conduit 12 is composed preferably of longitudinally corrugated metal sheets 23 and 23^a having their side edges interlocked to form a gas tight joint as indicated at 24, and their transverse ends may be provided with short out-turned flanges 25 (Fig. 2). Said sheets are preferably assembled out of parallelism with one another in order to gradually diminish the cross-sectional area of the conduit near the outlet end thereof, the purpose of which will appear presently, and the longitudinal corrugations of said walls 23 and 23^a, not only increase the heat radiating area thereof but also provide for expansion and contraction of the conduit.

Headers 10 and 11 are preferably cast across the opposite flanged ends of the muffler conduit 12 during the formation process of the headers, the casting of the metal of the headers around the flanged ends of said metal sheets being employed to effect a gas tight connection therebetween, or said headers may be welded or otherwise secured to the ends of the sheets.

The edges of the end walls 15 and 22 of the heater casing are grooved as indicated at 26 and 27 respectively to receive the ends of a sheet metal casing 28 hereinbefore mentioned, said casing being fashioned to conform to the shape of said end walls, and having its longitudinal edges overlapping and riveted together as indicated at 29 (Fig. 3). Stay bolts 30 extending through suitable apertures in each of said end walls, tie said ends together and clamp the casing wall 28 therebetween.

To close the space between the longitudinal sides of the conduit 12 and the casing wall 28, longitudinal angle strips 31 may be provided if found desirable, said strips being riveted or otherwise secured to the wall 28 along one flange of each strip with the other flange engaged with or secured to the interlocked edges 24 of said sheets forming the conduit, as shown in Fig. 3, the space within the casing below the conduit being thus separated from the space above except that said spaces are in communication at the rear end of the casing beyond the header 11. The top of the casing wall 28 adjacent the said radiating fins 18, is formed with a flanged opening 32 forming an outlet end

adapted to be connected with any suitable pipe (not shown) for conveying heated air into the interior of an automobile with which the device is used.

- 5 In operation, the exhaust gases from the vehicle engine (not shown) rush through the exhaust pipe 16 (which is the usual exhaust pipe of the engine) into the inlet header 10 contacting with the depending 10 wall 14 which deflects the flow abruptly, thus decreasing the velocity of travel. Moving past said flange and into the open end of the corrugated conduit 12, the gases flow therethrough within the channels formed by 15 the corrugations, and the heat of these gases is rapidly dissipated by the thin sheet metal walls of the conduit which have a maximum heat radiating area, and the gradual decrease in the cross-sectional area of the conduit 20 provides for shrinkage in volume of exhaust gases due to drop in temperature. Furthermore, by providing a substantially straight path of flow for the exhaust gases, back pressure is reduced to a minimum, and 25 as the gases pass into the exhaust header 11, they are somewhat retarded and permitted to expand so that as they pass out through the exhaust pipe 20, they will issue therefrom without noise.
- 30 Atmospheric air enters the heater casing through the opening 17 in the forward end wall 15 thereof and flows longitudinally of and beneath the conduit 12 in contact therewith to the rear end of the casing, thence 35 upward around the outlet header 11, and back to the forward end of the casing over said conduit in contact therewith and with the fins 18 on the outlet header 11 to the outlet 32 from which the air thus heated passes 40 into the interior of the vehicle.

A combined exhaust muffler and air heater is thus provided, which muffler affords a maximum of heating area to rapidly heat air which is conducted into the vehicle and 45 in which muffler back pressure is reduced to a minimum and from which the exhaust gases are expelled without noise. Heated air uncontaminated by exhaust gases is supplied to heat the car, and a device of simple 50 construction and which is cheap to manufacture, is provided. Combining of muffler and heater makes for compactness and simplicity of construction, eliminating the complications incident to manifold heaters as 55 commonly constructed.

Obviously changes may be made in the construction and arrangement, within the

scope of the appended claims without departing from the present invention, and such changes are contemplated.

60

What I claim is:—

1. A combined heater and muffler including a casing having an air inlet at one end and in the lower part thereof and a hot air outlet at the same end and in the upper part 65 thereof, a muffling device in said casing extending horizontally across the same from side to side thereof and from one end to adjacent the opposite end, said muffling device including a conduit for hot gases 70 extending longitudinally of the casing and constructed to permit expansion of hot gases passing therethrough, the walls of said conduit being of thin metal and having an extended heat radiating area.

75

2. A device as defined in claim 1 and wherein the walls of said conduit are formed of sheet metal with longitudinally extending corrugations.

3. A device as defined in claim 1 and 80 wherein said muffling device is formed with end expansion chambers and said conduit connecting said chambers, said conduit being comparatively thin in vertical dimension and with its walls formed of corrugated 85 sheet metal.

4. A combined muffler and heater including a casing having an air inlet opening in the lower part thereof and a hot air outlet in its upper part, a muffling device in said 90 casing including hollow headers and a corrugated sheet metal conduit connecting said headers, one of said headers having an inlet for hot gases and the other header having an outlet for the gases extending through 95 the opposite end of the casing, one of said headers being spaced from the casing end and within the same and said conduit being of a width to extend horizontally across the casing and divide the same into air passages 100 above and below said conduit, said passages being in communication at one end of said casing between the header and the end of the casing, said headers forming expansion 105 chambers for the hot gases passing through the muffling device and said conduit being of decreasing cross-sectional area throughout its length, whereby the hot gases passing through said device are cooled by radiation and retarded and the heat is imparted to 110 the air passing through said casing.

105

In testimony whereof I affix my signature.

JAMES W. KEENAN.
